The ornamental design for a surveillance camera enclosure, as shown and described.

DESCRIPTION

FIG. 1 is a front, top, and right side perspective view of a surveillance camera enclosure, shown in condition of use with a sample environment disclosed in broken lines;

FIG. 2 is a front, top, and right side perspective view of the surveillance camera enclosure shown in FIG. 1 with the sample environment removed for ease of illustration;

FIG. 3 is a top plan view thereof;

FIG. 4 is a front elevational view thereof;

FIG. 5 is a left side elevational view thereof;

FIG. 6 is a right side elevational view thereof;

FIG. 7 is a rear elevational view thereof; and,

FIG. 8 is a bottom plan view thereof.

The broken lines depict portions of the surveillance camera enclosure in which the design is embodied that form no part of the claimed design. The broken lines showing a sample environment in FIG. 1 represent environmental structure and form no part of the claimed design.
